UNITED STATES PATENT OFFICE.

WARREN W. GORE, OF BELOIT, WISCONSIN, ASSIGNOR TO FAIRBANKS, MORSE & COMPANY, OF CHICAGO, ILLINOIS, A CORPORATION OF ILLINOIS.

INTERNAL-COMBUSTION ENGINE.

1,110,438.

Specification of Letters Patent. Patented Sept. 15, 1914.

Application filed April 20, 1912. Serial No. 692,179.

To all whom it may concern:

Be it known that I, WARREN W. GORE, a citizen of the United States, residing at Beloit, in the county of Rock and State of Wisconsin, have invented a certain new and useful Improvement in Internal-Combustion Engines, of which the following is a specification.

My invention relates to internal combustion engines and more particularly the mechanism whereby the combustible gas or vapor is generated and supplied to the engine.

The object of the invention is to provide means whereby the engine may be made to both operate and start on kerosene or oils somewhat heavier than kerosene.

I accomplish my object by the mechanism illustrated in the accompanying drawings in which—

20 Figure 1 is a perspective view of an engine equipped with my special apparatus. Fig. 2 is a detail showing in vertical section the oil reservoir and associated parts. Fig. 3 is a section on the line 3—3, Fig. 2.

25 The engine is of the ordinary type in which a charge of air is drawn in by the piston, while at the same time the suction charges this air with the necessary amount of liquid fuel vapor to form an explosive mixture. In the form selected to illustrate the invention the cylinder 1 is supplied with the explosive mixture through the intake 2. This intake is connected with a cross 3 to which ordinary cold atmospheric air is supplied through the nipple 4.

30 Hot air is supplied through a pipe 5 which leads from a drum or jacket 6, open at some point to the atmosphere and surrounding the engine exhaust pipe 7. The hot gases issuing from the exhaust heat the air in said jacket and thus is furnished a constant supply of pure warm air to the intake if desired. The pipes 4 and 5 are supplied with suitable dampers 4^a and 5^a respectively whereby the flow to the intake may be regulated. Extending downward from the cross 3 is a pipe 10 closed at the lower end by a cap 11, these two parts forming a retort as will hereinafter appear.

35 Oil is supplied to the retort through pipe 12 provided with a sight feed 13 leading from the oil reservoir 14. This latter is adapted to contain heavy oil such as kerosene or heavier oil and constructed in any suitable manner for example, as shown in

Richardson Patent No. 690,610. In the form here shown the reservoir has two compartments 14^a and 14^b, one for containing kerosene and the other for containing water. The flow to the intake 2 is through ducts 14^c and 14^d respectively controlled by valves 14^e and 14^f respectively. The water reservoir and its connections may, however, be omitted as they form no part of my present invention. The flow from pipe 12 and sight feed 13 is controlled by a spigot 15, consequently oil can flow by gravity from the reservoir into the retort and be afterward shut off by the operator after the engine has started running. A torch or burner 20 is located in position to heat the retort, said burner being supported in any suitable manner, for example, by bracket 21, secured to the retort.

40 It will be understood that the engine is to be both started and operated on heavy oil. With this in view, the reservoir will be filled with such oil preparatory to starting. When ready to start, the attendant opens the spigot 15 and permits a limited amount of oil to 45 gravitate into the retort 10. At the same time burner 20 is lighted and the flames thereof heat the retort to such a degree as to generate an explosive vapor. By preference, damper 5^a will be opened at first and damper 4^a closed so that the mixture supplied to the engine intake 2 will be warmed. The engine is thus supplied with a readily combustible mixture upon which it can start. After it has run long enough to get the parts well 50 heated the spigot 15 can be turned off, and the engine will run on the oil drawn direct from one of the compartments of the reservoir. The damper 4^a may be left closed in order that the incoming fresh air may be 55 heated, or it may be opened and the air partially or entirely supplied through the nipple 4. If cold air is wanted, damper 5^a will be closed. By regulating the openings of dampers 4^a and 5^a the proper temperature 60 may be obtained.

55 It will thus be seen that the engine is enabled to start with the same heavy oil upon which it ultimately runs, the attendant being able to divert part of the oil to the retort for starting and then stop the flow to the retort and permit the oil to be taken direct from reservoir 14 into the intake 2. No additional moving parts are required with the exception of the valves, and the starting or 65

vapor-generating apparatus forms a constituent part of the machine.

Having thus described my invention what I claim as new and desire to secure by Letters Patent is:

1. In an internal combustion engine the combination with the engine cylinder and intake of a reservoir adapted to supply heavy oil to said intake, a cross communicating with said intake, a retort communicating with said cross, a valved duct leading from said reservoir to said retort and two ducts leading to said cross for supplying air thereto, one of said ducts leading from the atmosphere and the other being adapted to supply heated air to said cross.
2. In an internal combustion engine the combination with the engine cylinder and intake of a reservoir adapted to supply heavy oil to said intake, a retort, a valved duct leading from said reservoir to said retort, means for supplying air to said intake, and means for controlling the amount and the temperature of the air admitted to said intake.
3. In an internal combustion engine the combination with the engine cylinder and intake of a reservoir adapted to supply heavy oil to said intake, a retort, a valved

duct leading by gravity from said reservoir to said retort, a duct leading to said intake from the atmosphere, a damper in said duct, a drum open to the atmosphere and encircling the engine exhaust, a duct leading from said drum to said intake, and a damper in the last mentioned duct.

4. In an internal combustion engine the combination with the engine cylinder and intake of a reservoir adapted to supply heavy oil to said intake, a cross communicating with said intake, a pipe leading downward from said cross and having a closure at the end, a valved duct leading by gravity from said oil reservoir to said pipe, a heater for said pipe, an air duct open to the atmosphere leading to said cross, a damper on said air duct, a drum at the engine exhaust, a duct leading from said drum to said cross, and a damper in the last mentioned duct, all coöperating in the manner and for the purpose described.

In witness whereof, I have hereunto subscribed my name in the presence of two witnesses.

WARREN W. GORE.
